UNITED STATES PATENT OFFICE.

WILLIAM BEDFORD WATSON, OF JACKSONVILLE, FLORIDA.

RAILROAD-CROSSING GATE.

Application filed March 30, 1926. Serial No. 98,587.

The invention relates to safety means for minimizing casualties at railroad crossings and aims to provide a gate at each side of the railroad which normally is housed within 5 a pit and which is automatically projected into operative position upon the approach of a train in either direction, the gates being returned to normal position after the train has passed the crossing.

10 The invention relates to electrically operated mechanisms including motors, brakes and switches, which are controlled by the train, the circuits being automatically closed by the train when it has approached the crossing a predetermined distance and said circuits being automatically broken and brakes applied when the mechanisms have reached a given point in their operation, thereby preventing an overthrow of the 15 gates in either direction and insuring their return to closed position after the necessity of guarding the crossing has passed.

20 The invention furthermore contemplates a closing plate for the pit in which the gate is housed, applied to and movable with the gate, thereby preventing any obstruction or interference with the free movements of the gate or the closure for the gate receiving pit.

25 Any suitable electrical appliances may be employed as adjunctive and accessory to the gate operating mechanisms, hence in the practical embodiment of the invention it is to be understood that in adapting the means to meet specific needs and requirements the design may be varied, and such other changes in the minor details of construction may be resorted to within the scope of the 30 invention as claimed, without departing from the spirit thereof.

35 For a full understanding of the invention and the merits thereof, reference is to be had to the following description and the drawings hereto attached in which,—

40 Figure 1 is a diagrammatical view of a railroad crossing provided with safety means embodying the invention.

45 Figure 2 is an enlarged sectional view on the line 2—2 of Figure 1, showing the gate elevated.

50 Figure 3 is an enlarged sectional view on the line 3—3 of Figure 1,

55 Figure 4 is a detail top plan view of the gate and the operating mechanism associated therewith showing the parts on an en-

larged scale, the cover of the pit being omitted.

Figure 5 is a side view of the gate.

Figure 6 is an enlarged detail sectional view on the line 6—6 of Figure 5, a portion 60 of one of the struts being broken away,

Figure 7 is an enlarged detail sectional view on the line 7—7 of Figure 5,

Figure 8 is an enlarged elevational view 65 of an end member,

Figure 9 is an edge view of the end member, and

Figure 10 is a diagrammatical view 70 designed to illustrate the circuits.

Corresponding and like parts are referred 75 to in the following description and designated in the several views of the drawings by like reference characters.

Referring more particularly to Figure 1 80 of the drawings, the numerals 1 and 2 designate the tracks of a railroad and 3 the street, road or other thoroughfare crossing the same. In accordance with the invention, a gate is located at the crossing upon each side 85 of the railroad and is normally housed within a pit 4 so as to be out of the way when not required to give protection. The operating mechanism is located within a pit 5 adjacent the pit 4 and in communication therewith. The two pits, 4 and 5, are closed 90 by suitable covers which are flush with the surface. The cover for the pit 4 is designated by the numeral 6 and is attached to the gate to move therewith. The cover for the pit 5 consists of a metal plate 7 which 95 is fitted into a shouldered frame 8 located at the mouth of the pit. Suitable circuit closing devices 9 and 10 are located along the line of the tracks at a predetermined distance from the crossing and these devices 100 are train operated to insure projection of the gates upon the approach of a train and return of the gates to closed position after the train has passed the crossing.

105 In this connection, it is observed that suitable electric conductors are interposed between the respective circuit closing devices and the electrically operated gate actuating mechanisms, and these conductors may be arranged in any preferred way either underground or over head so as to be out of the way.

The gates may be of any preferred construction and preferably consist of metal bars and as shown, the gate comprises an upper bar 10, a lower bar 11, end bars 12 110

and intermediate struts 13, suitable braces 14 being provided to stiffen and reinforce the structure. The braces 14 are connected to circular plates 15 which are riveted to the struts 13. The braces, struts and upper and lower members may consist of angle irons, as indicated most clearly in the detail views of the gate. The upper and lower longitudinal members may consist of or be reinforced by means of angle bars 16, as indicated most clearly in Figure 6. Vertically disposed rack bars 17 are located at the ends and intermediate the ends of the gates and constitute means for moving the gates vertically when opening and closing the same. A gear wheel 18 coacts with each of the rack bars 17 and is in mesh therewith and is fast to a shaft 19 mounted in suitable bearings 20 and this shaft is positively rotated in each direction to elevate or lower the gates as required. It is to be understood that the gate is mounted so as to move vertically in a given plane without any binding action and for this purpose grooved rollers 21 are provided and mounted in brackets 22. The grooved rollers 21 engage flanges of the struts 13 and are located upon one side of the gate whereas the shaft 19 and gear wheels 18 are disposed upon the opposite side of the gate which is thus held in place and directed in its vertical movements.

The numeral 23 designates an electric motor which may be connected with the shaft 19 in any preferred way and as indicated, a sprocket drive chain 24 connects, sprocket wheels 25 and 26 fast to the respective shafts 19 and 27, the latter designating the shaft of the motor. The numeral 28 designates a solenoid brake which may be of the self contained floor mounted type unless a motor mounted type is preferred. The solenoid may be enclosed, ventilated and made rain proof and will be suitable for operation on circuits having a high, normal, or lower voltage. The numeral 29 designates a magnetic reversible switch and 30 a limit switch of the geared type having two normally closed contacts 31 and 31^a adapted to be operated by a traveling nut 32 which can be adjusted to stop the motor at the required point. The limit switch 30 is enclosed in a weatherproof case, as indicated in Figure 4.

In the installation of the invention, the contact switches 9 and 10 are located any determinate distance from the crossing, as for instance, a mile, more or less, and positioned to operate the magnetic switch 29, which in turn controls the current to the motor 23 and the solenoid brake 28. The switches 9 and 10 may be of any type or design usually employed to be closed by a moving train and which normally are open. The reversible switch 29 comprises electro-

shaft 35 and a plurality of arms 36, 36^a, 36^b and 36^c projecting from the rock shaft 35. When the train approaches the crossing from the right, as indicated by the arrow in Figure 10, and reaches the switch 9, the latter is actuated to close the circuit through the electromagnet 33 which becoming energized attracts one end of the armature and rocks the shaft 35 to close the circuits through the motor 23 and the solenoid of the brake mechanisms 28. Thus, the brake is released at the same instant that current is supplied to the motor. The gate is now elevated and at the same time the limit switch is actuated by rotation of the threaded shaft 37 carrying the nut 32. When the gate reaches the limit of its upward movement the nut 32 has approached the end of its travel in one direction and operated the circuit closer 31 to break the circuit to the motor 23 and solenoid of the brake 28. The instant the motor stops the brake is applied and holds the gate elevated. The gates are elevated before the train approaches the crossing and remain up until the train reaches a point to operate the switch 10 and close the circuit through the electromagnet 33^a, thereby reversing the armature 34 and shaft 35 and again closing the circuit through the motor 23 and the solenoid of the brake 28. The motor is now reversed and the gate lowered. During this movement the nut 32 travels in an opposite direction and when the gate is fully lowered the nut 32 of the limit switch actuates the switch 31^a and interrupts the motor and brake circuits, thereby stopping the motor and setting the brake to hold the gate in lowered position until the circuit closer 9 is again actuated by the next train approaching the crossing. The several parts, the motor 23, the solenoid brake 28, the reversible switch 29 and the limit switch 30 are of well known construction but are combined in a novel manner to operate in the manner set forth in a railroad gate crossing.

The feed wires of the power lines are indicated at 38 and 39 respectively, and the return wire at 40. Connecting the switch arms 36 and 36^b with the feed wires 38 and 39 are wires 41 and 42, and connecting the switch arm 36^a with the return wire 40 is a wire 43. Corresponding terminals of the reversible switch are indicated at 44, 45, 46 and 47 and the opposite corresponding terminals of said switch at 48, 49, 50 and 51, the switch arms being movable in one direction to engage the former set of terminals and in the other direction to engage the latter set of terminals. Connecting the end terminals of the motor 23 with the switch terminals 44 and 48 are wires 52 and 53, and connecting the middle terminal of the motor with the switch terminals 45 and 49 is a wire 54. Connecting the wire 52 with the switch terminal 50 is a wire 55, and connect-

ing the wire 53 with the switch terminal 46 is a wire 56. Leading from the wire 41 is a wire 57 which is connected to both of the switch terminals 47 and 51, and connecting 5 the solenoid brake 28 in the motor circuit are wires 58.

The terminal of the track switch 9 is indicated at 9^a, and connecting said terminal with the feed wire 38 is a wire 59. The terminals of the limit switch 30 are indicated at 60 and 61, and connecting the blade of the switch 9 with said terminals is a wire 62. Leading from the switch contact 31 to the magnet 33 of the reversible switch is a wire 15 63, and leading from said magnet to the return wire 40 is a wire 64. The terminal of the switch 10 is indicated at 10^a, and connecting said terminal with the feed wire 38 is a wire 65. Connecting the blade of the 20 switch 10 with the wire 62 as well as with the switch arm 36^c is a wire 66, and connecting the switch contact 31^a with the magnet 33^a of the reversible switch is a wire 67. Leading from said magnet to the return wire 25 40 is a wire 68.

The reversing switch normally stands in the open position shown in Figure 10 and it will now be assumed that the switch 9 is closed by a train approaching from the 30 right, as previously indicated. Current will then flow from the wire 38 through the wire 59, switch 9, wire 62, contact 31, wire 63, and the electro-magnet 33 to return through the wire 64 to the wire 40. Thus the electro- 35 magnet 33 will be energized so that the reversing switch 29 will be rocked to the right to engage the switch arms 36, 36^a, 36^b, and 36^c, with the terminals 44, 45, 46 and 47. Current will then flow from the wire 38 40 through the wire 41, switch arm 36, and wire 52 to one end terminal of the motor 23, while current will also flow from the wire 39 through the wire 42, the switch arm 36^b, the wire 56 and wire 53 to the other end terminal 45 of the motor, whence the current will return through the wire 54, switch terminal 45, switch arm 36^a and the wire 43 to the wire 40. The motor 23 will thus be set into 50 operation for raising the gate.

Attention is now directed to the fact that since the switch arm 36^c is rocked to engage the terminal 47 coincident with the energization of the motor, current will flow from the wire 38 through the wire 41, the wire 57, the terminal 47, the switch arm 36^c, the wire 66, the wire 62, the switch contact 31, the wire 63, the electro-magnet 33 and the wire 64 to return to the wire 40. Accordingly, even should the train travel past the switch 60 9 so that said switch would be permitted to open, the energization of the electro-magnet 33 will, nevertheless, be maintained for keeping the motor circuit closed until the gate has reached the limit of its upward travel.

65 When this occurs, the nut 32 will engage the

contact 31 and shift said contact out of engagement with the terminal 60 so that, as will be perceived, the circuit last traced through the electro-magnet 33 will be broken, when the reversing switch 29 will 70 return to its normal open position for de-energizing the motor.

Assuming now that the gate is raised, the switch 10 will, as previously described, be closed by the train as said train proceeds 75 along the track. Current will then flow from the wire 38 through the wire 65, the switch 10, the wire 66, the wire 62, the switch contact 31^a, the wire 67, and the electro-magnet 33^a to return through the wire 68 to 80 the wire 40. The electro-magnet 33^a will thus be energized for rocking the reversing switch to the left to engage the switch arms 36, 36^a, 36^b, and 36^c with the switch terminals 48, 49, 50 and 51. As will be seen, the 85 motor circuit previously traced will be closed but, in this connection, attention is directed to the fact that the connections are such that the motor 23 will be turned in a direction opposite to its former direction of movement 90 for lowering the gate. Since the switch arm 36^c is rocked to engage the terminal 51 coincident with the energization of the motor, current will flow from the wire 38 through the wire 41, the wire 57, the switch terminal 95 51, the switch arm 36^c, the wire 66, the wire 62, the switch contact 31^a, the wire 67 and the electro-magnet 33^a to return through the wire 68 to the wire 40. Accordingly, should the train travel past the switch 10 so that the said switch would be permitted to open, the energization of the electro-magnet 33^a will be maintained for keeping the motor 100 circuit closed until the gate has reached the end of its downward travel. When this occurs, the nut 32 will engage the switch contact 31^a and shift said contact to open position for breaking the circuit last traced through the electro-magnet 33^a, when the reversing switch 29 will return to its normal 105 position for stopping the motor. Thus, the gate will be raised and lowered automatically. When the motor circuit is closed by the closing of the switch 9, current will flow from the wire 52 through one of the wires 110 58 and through the solenoid of the solenoid brake 28 to return to the wire 54 through the other of the wires 58. Accordingly, the brake will be released coincident with the energization of the motor. As will be perceived, like results will follow when the switch 10 is closed and since the circuit of the solenoid brake will be broken coincident with the breaking of the motor circuit, the 115 brake will be applied coincident with the de-energization of the motor.

Having thus described the invention, I claim:

1. Protective means for a railroad crossing comprising a gate, operating means for 120

- the gate including an electric motor, an electrically operated brake for the motor, a current supplying circuit for the motor and brake, an electrically operated automatic switch for closing the circuit through the motor and the electrically operated brake mechanism to simultaneously start the motor and release the brake, and electrically actuated means for operating the said automatic switch contained in a circuit deriving current from the same source as the motor and including a train operated switch.
2. Protective means for a railroad crossing comprising a gate, operating means for the gate including an electric motor, an electrically operated brake for the motor, a current supplying circuit for the motor and brake, an electrically operated automatic switch for closing the circuit through the motor and the electrically operated brake mechanism to simultaneously start the motor and release the brake, and electrically actuated means for operating the said automatic switch contained in a circuit deriving current from the same source as the motor and including a train operated switch, and a limit switch in circuit with the said electrically actuated means and operated by the motor to break the circuit thereof and the circuits of the brake operating mechanism and the automatic switch actuating mechanism.
3. Protective means for a railroad crossing comprising a gate, operating means for the gate including a reversible electric motor, a current supplying circuit for the motor, a reversible switch for controlling the supply of electricity to the motor, a time limit switch actuated by the motor for breaking the circuit when the gate is at the limit of its movement in each direction, and electrically operated means for the said reversible switch included in a circuit deriving current from the same source as the motor and containing two train operated switches located upon opposite sides of the gate.
4. Protective means for a railroad crossing comprising a gate, operating means for the gate including a reversible electric motor, a current supplying circuit for the motor, a reversible switch for controlling the supply of electricity to the motor, a time switch actuated by the motor for breaking the circuit when the gate is at the limit of its movement in each direction, electrically operated means for the said reversible switch included in a circuit deriving current from the same source as the motor and containing two train operated switches located upon opposite sides of the gate and a limit switch actuated by the motor and in circuit with the reversible switch, operating means to break the several circuits.
5. Protective means for a railroad crossing comprising a gate, operating means for the gate including a reversible electric motor, an electric brake for the motor, a current supplying circuit for the motor and brake, a reversible switch for controlling the supply of electricity to the motor and brake, a time limit switch actuated by the motor for breaking the circuit when the gate is at the limit of its movement in each direction, electrically operated means for the said reversible switch included in a circuit deriving current from the same source as the motor and containing two train operated switches located upon opposite sides of the gate and a limit switch actuated by the motor and in circuit with the reversible switch operating means to break the several circuits.

In testimony whereof I affix my signature.

WILLIAM BEDFORD WATSON. [L. S.]
